Patented Aug. 24, 1971

221,533

SQUAD CAR EQUIPMENT CONSOLE OR SIMILAR ARTICLE

Lyle M. Browning, 1408 Garrett St.,
Yakima, Wash. 98902

Filed July 10, 1969, Ser. No. 18,170

Term of patent 14 years

Int. Cl. D12—14

U.S. Cl. D14—6

FIG. 1

FIG. 2

FIG. 3

FIG. 4

FIG. 1 is a left front isometric view of the squad car equipment console or similar article embodying my new design;

FIG. 2 is a top plan view thereof;

FIG. 3 is a side elevational view thereof;

FIG. 4 is the side opposite FIG. 1.

The elements shown in broken lines are included for illustrative purposes only.

I claim:

The ornamental design for a squad car equipment console or similar article, substantially as shown and described.
